UNITED STATES PATENT OFFICE.

JAMES H. KUHNS, OF TULSA, OKLAHOMA.

SWIVEL-SOCKET FOR OIL AND GAS WELL DRILLS.

1,212,962.

Specification of Letters Patent. Patented Jan. 16, 1917.

Application filed September 16, 1915. Serial No. 51,020.

To all whom it may concern:

Be it known that I, JAMES H. KUHNS, a citizen of the United States, and a resident of Tulsa, in the county of Tulsa and State of Oklahoma, have invented a certain new and useful Improvement in Swivel-Sockets for Oil and Gas Well Drills, of which the following is a specification.

One of the principal objects of my invention is to provide an improved swivel joint in which hardened shoulders are provided against which the swivel member or collar to which the lower end of the cable is connected, may bear, so that a strong, long wearing construction is provided.

A further object of the invention is to provide an improved swivel joint in the nature of detachably connected barrel sections, through which the cable extends, and in which a swivel member or collar is adapted to play, said collar being connected to the lower end of the cable, the construction being such that the collar or swivel member will not bind against any of the parts of the device.

A further object of the invention is to provide a device of the class described which will be extremely simple, durable, efficient in operation, and inexpensive to manufacture.

With these and other objects in view which will become apparent as the description proceeds, the invention resides in the construction, combination, and arrangement of parts hereinafter more fully described and claimed, and illustrated in the accompanying drawing in which like characters of reference indicate like parts throughout the several figures, of which—

Figure 1 represents a view in elevation of a swivel joint constructed according to my invention. Fig. 2 represents a vertical longitudinal sectional view taken therethrough. Fig. 3 represents a view similar to Fig. 1, showing the position of the parts after the spring has been removed. Fig. 4 represents a view in section taken horizontally on the plane indicated by the line 4—4 of Fig. 2.

Referring more particularly to the drawing, 5 indicates the upper and 6 the lower barrel section. Each is provided with a squared portion 7 for the reception of a wrench or other tool to be used in connecting and disconnecting the sections. The upper section has a reduced, threaded, conical lower

end 8 which is adapted to be turned into the internally threaded conically bored upper end 9 of the lower section 6. Below the conical portion 8, said upper section extends as 60 at 10 into the bore 11 provided longitudinally of the lower section. The section 6 adjacent the lower end of the bore is provided with openings or perforations 12 for drainage purposes. The extension 10 is provided with a passage or duct 13 which establishes communication between the bore 14 provided in section 5, and the bore 11 in the lower section 6. This bore 14 is of less diameter than the bore 11 and through the former 70 extends the cable 15. At its lower end, this cable depends within bore 11 and passes through a collar or swivel member 16 of annular formation which is arranged within the bore 11. This collar or swivel member is 75 of a diameter somewhat less than the diameter of the bore so as to be capable of ready sliding and rotary movement therein. The lower end of cable 15 is babbitted within the collar 16 as at 17. Disposed upon the cable 80 15 between the collar 16 and the annular shoulder 18 provided at the lower end of the extension 10, is a coiled spring 19.

The spring 19 is used as a cushioning device while spudding in and during the first 85 few hundred feet of drilling, after which the top section 5 is unscrewed from the lower section, the wire line is cut off below the spring, the latter removed, the line reinserted within the collar, and rebabbitted. 90 The sections of the device are then connected together and when in this position as indicated in Fig. 3, the swivel member or collar 16 rests against the shoulder 18 provided at the lower end of the extension 10. When 95 in this position, the collar or swivel member may readily rotate without hindrance within the lower section. The lower end of section 6 is provided as indicated at 20, with a threaded conical socket into which may be 100 turned the upper end of a drilling tool. When the spring is removed the swivel member or collar rests directly against the shoulder 18 when the device is in operation.

It often happens that while the tool is being pulled, fine sand settles around the cable 13, when the block 16 is tight up against the lower end of the projection 10. The sand soon becomes packed in around the cable and unless constant drainage is provided, the 110 tool will become stuck and will not effectively operate. The passage 13 provided in

BEST AVAILABLE COP

1,212,962

the extension has been found to effectually eliminate this trouble and to afford a constant drainage around the cable, so that even after the tool has been idle for a long time, 5 the fine sand and silt will not have become packed around the cable.

One of the peculiar advantages accruing to my device is that the extension 10, as well as the upper end of the collar or swivel 10 member 16, may be case-hardened if so desired, while in many other devices of this nature, the shoulder for receiving the strain is so arranged with respect to the section on which it is formed, that it cannot be case-hardened, and hence wears out in a comparatively short time. Furthermore, in this device the uniform diameter of the barrel member 6 prevents wedging of the collar within the same, and the load or strain is received on the square shoulder 18 and on the upper end of the collar 16 so that the device may revolve upon the collar as a pivot.

Although I have described the preferred embodiment of my invention, I may desire 25 to make such changes in the construction, combination, and arrangement of parts thereof, as do not depart from the spirit of the invention and the scope of the appended claims.

30 I claim:—

1. A device of the class described, comprising an upper and a lower section threadedly connected together, and provided with alining bores, the bore in the lower section 35 being of a larger diameter than the bore in the upper section, an extension carried by the upper section and arranged within the bore in the lower section, said extension being provided with a passageway communicating 40 with the bores in the sections, and a cable extending through the upper section and into the lower section and being provided with a collar arranged within the lower section adapted to engage and swivel 45 against the said extension, said cable being babbitted within the collar.

2. A device of the class described comprising a pair of detachably connected sections, said sections being provided with

alining bores, an extension formed on one 50 of the sections and extending within the bore in the other section, and being provided with a passageway communicating with the bores in the sections, a flexible element extending through the bore in the said one section and into the bore in the other section and being provided with a swivel member adapted to engage against said extension.

3. A device of the class described, comprising a pair of hollow sections detachably 60 connected together, an extension formed on one of the sections and extending within the other and provided with a passage connecting the interiors of the sections, and a flexible element extending into the sections and 65 being provided with a swivel member adapted to engage against said extension.

4. A device of the class described, including an upper and a lower section provided with alining bores, the bore in the lower section being larger than the bore in the upper section, said upper section being provided with a tapered externally threaded portion screwed into an internally threaded tapered socket in the lower section and having a tempered extension projecting into the bore of the lower section, a cable extending through the upper section into the lower section, and a collar carried by the cable within the lower section and adapted to engage against said 80 extension.

5. A device of the class described including an upper and a lower section, said sections being provided with alining bores, an extension formed on one of the sections extending within the other and provided with a passage connecting the bores in the sections, a flexible element extending into the sections and provided with a swivel member adapted to engage against the extension, the 85 section in which the swivel member operates being provided with means whereby it may be drained.

JAMES H. KUHNS.
